Seay, etc.

United States Patent Office.

EDWARD MOORE, OF PORTLAND, MAINE.

Design No. 3,078, dated June 30, 1868.

DESIGN FOR A BADGE.

The Schedule referred to in these Letters Patent and making part of the same.

TO ALL WHOM IT MAY CONCERN:

Be it known that I, EDWARD MOORE, of Portland, in the county of Cumberland, and State of Maine, have originated and invented a new and useful Design for a Badge; and I hereby declare the following to be a full, clear, and exact description thereof, which will enable others to make and use my invention and design, reference being had to the accompanying drawings, making part of this specification, in which is shown a view of the design.

My invention is a design for a badge to be worn upon the person or the clothing, and consists of the following parts, viz:

An oval frame or casing, *a*, upon which the words, "I will fight it out on this line if it takes all summer," are engraved. Within this frame or casing is set a portrait or picture. Around the outer edge of this casing *a* are set three scrolls, as shown in the drawing at *b b' b''* of the figure and pattern set forth therein.

Upon the top edge of the frame *a* is set an eagle, *c*, with wings extended, and bearing in its beak arrows *d*. At the bottom of the frame is a star, *e*.

The words above set forth conform to the curvature of the casing, commencing at the left and reading to the right side. The scrolls and eagle may be gilt or otherwise, according to the material employed in the construction of the badge.

What I claim as my invention, and desire to secure by Letters Patent, is—
The design for a badge herein shown and described.

EDWARD MOORE.
